UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

MACHINE FOR SHAPING LIPPED SOLES.

Application filed June 28, 1920. Serial No. 392,389.

To all whom it may concern:

Be it known that I, JOHN W. COSGROVE, a citizen of the United States, residing at Medford, in the county of Middlesex and State of Massachusetts, have invented certain new and useful Improvements in Machines for Shaping Lipped Soles; and I do hereby declare the following to be a full, clear, and exact description of the invention, such as will enable others skilled in the art to which it appertains to make and use the same.

The present invention relates to machines for operating upon lipped soles during their process of manufacture and more particularly to machines for shaping and setting the lips of insoles.

The object of the invention is to re-organize machines of the above named general character and to provide certain improvements in their construction and mode of operation for the purpose of increasing their efficiency, rendering unnecessary certain adjustments of the operating parts, and enabling the sole to be properly located for the operation to be performed thereon without the employment of special positioning devices.

To the accomplishment of this object and such others as may hereinafter appear, the invention resides in the features of construction and combinations of parts hereinafter described and particularly pointed out in the appended claims, the advantages of which will be apparent to those skilled in the art.

The invention will be best understood by reference to the accompanying drawings, in which the invention is illustrated in its preferred form as embodied in a machine for shaping and setting the lip at the toe of an insole.

In the drawings, Figure 1 is a view, in front elevation, of the machine; Fig. 2 is a view, in side elevation thereof, looking from the left in Fig. 1, Fig. 3 is a plan view of the machine; Figs. 4 and 5 are detail views in plan and front elevation, respectively, of the work table; Fig. 6 is a section on the line 6—6 of Fig. 3; Fig. 7 is a detail plan view, on an enlarged scale, of the inner form or mold; Fig. 8 is a view, in side elevation, of the form or mold shown in Fig. 7; Fig.

9 is a section on the line 9—9 of Fig. 7; Fig. 10 is a detail plan view, on an enlarged scale, of the outer form or mold; and Fig. 11 is a view, in side elevation, of the form shown in Fig. 10.

As shown in Figs. 1, 2 and 6, the working parts of the machine are mounted on a hollow head 12 and are supported at a convenient height for the operator by a pedestal 14, to which the head is secured. The head 12 is of irregular shape, having two oppositely disposed upright sides 16 and a projecting front portion 18. The sides 16 of the head are provided with bearings 20 for a horizontal main shaft 22, and are extended upwardly above the bearings 20 to support a fixed rod 24, upon which certain actuating levers are pivoted, as will be hereinafter described. Secured to the upper face of the portion 18 of the head is a work table 26, by means of which the insoles are supported while they are being operated upon.

The lip shaping and setting operation is performed by two cooperating molds or forms 30 and 32 (Fig. 2 and 6) which are shaped to engage the outer and inner sides, respectively, of the lip at the toe of the insole. For convenience, the form 30 will hereinafter be referred to as the outer form or mold, and the form 32 as the inner form or mold. To enable the forms to perform their shaping and setting functions, the outer form 30 is constructed with a V-shaped notch 34, as illustrated in Fig. 10, and the inner form 32 is provided with a correspondingly shaped projection 36, as shown in Fig. 7, which is adapted to cooperate with the walls of the notch 34 to mold or shape the lip. Molds or forms of different shapes will be used for insoles having differently shaped toes, the forms illustrated in Figs. 7 and 10 being adapted for use upon insoles having comparatively narrow or peaked toes. Normally the outer form 30 is positioned, as shown in Figs. 2 and 6, at a sufficient elevation above the work table 26 to permit the insertion, between the form and the work table, of the feather at the toe of the insole, while at the same time the form is near enough to the work table to enable the opposite side walls of the notch 34 to be engaged by the lip of the insole as the latter is pushed rearwardly across the

100
105

work table by the operator. The outer form thus serves as a gage to position the insole longitudinally upon the work table for the performance of the lip shaping operation, 5 making it unnecessary to provide sole gages or other positioning devices. The inner form 32 is normally positioned somewhat higher above the work table than the outer form to facilitate the presentation of the insole to the latter. After the insole has been positioned on the work table by the engagement of the lip with the outer form, both the inner and outer forms are depressed until they are brought into pressing engagement 10 with the insole, the inner form engaging the face of the insole between the converging toe portions of the lip and the outer form engaging the feather of the insole, adjacent the point of the toe, so that the toe portion of the insole is flattened against the work table.

The mechanism for imparting to the inner form its insole pressing movements comprises a vertically movable slide 40 (Figs 2 and 6) to the lower end of which the inner form is secured, and cam actuated devices connected with the upper end of the slide. In order that the inner form may be readily removed from the slide 40, so that it may be 20 replaced by another form having a different contour, the form is conveniently provided with a transverse dove-tailed tongue 42 which is received in a correspondingly shaped groove 44 in the slide, and is secured 30 therein by means of a clamping screw 46, the lower end of the slide being slotted longitudinally, as shown at 48, to provide sufficient yielding movement of the walls of the groove. The slide 40 is freely movable vertically in a guideway 50, centrally formed 40 in a slide-carrier 52, and is provided, on each side of its upper end, with pivoted blocks 54 (see Figs. 1 and 2) that are mounted in the slotted bifurcated end 56 of a lever 45 58 which is pivoted on the fixed rod 24. The lever 58 is, in turn, actuated by a bell-crank lever 60 which is pivoted on the rod 24 alongside of the lever 58. One end of the bell-crank lever 60 carries a cam roll 62 50 which is received in a suitable cam groove in a cam disk 64 that is secured to the main shaft 22. The other end of the bell-crank lever 60 is yieldingly connected with the lever 58 by means comprising a rod 66 60 (Figs. 1, 2 and 3) which extends through an ear 68, projecting laterally from the lever 58, and is pivotally connected, by means of a stud 70, with the bifurcated end of the bell-crank lever 60, a shoulder 72 being formed adjacent the pivoted end of the rod 66 to bear against the under face of the ear 68. A spring 74 surrounding the rod 66, engages 65 at one end the ear 68 and at the opposite end an adjusting nut 76, normally holding the ear 68 in engagement with the shoulder 72.

The lever 58 tends normally to partake of the movements of the bell-crank lever 60, but yields when the inner form has been brought into pressing engagement with the insole. By turning the adjusting nut 76, 70 the amount of compression of the spring 74 may be adjusted to vary the pressure exerted by the inner form against the insole.

To adapt the machine for operation upon insoles of different thicknesses, provision is 75 made for adjusting the slide 40, and the form carried thereby, toward and from the work table. This is accomplished by an eccentric mounting of the pivotal supports for the blocks 54 carried on the upper end of the 80 slide 40. As shown in Figs. 1 and 6, a circular aperture is formed in the upper end of the slide 40, in which is mounted a cylindrical stud 80, the upper end of the slide being split as indicated at 82 and provided 85 with a clamping screw 84 so that the stud 80 may be clamped in any desired radial position. Projecting from the ends of the stud 80 are pins 85, the axes of which are coincident, but eccentric relatively to the axis 90 of the stud. These eccentric pins 85 extend through and constitute the pivotal supports for the blocks 54. The pins 85 are severally provided with screw-threaded axial holes, and in each of these holes is secured a screw 86, the head of each screw overlapping the outer face of a block 54 and serving to hold it within the slotted bifurcated end of the lever 58. By loosening the clamping screw 84 and turning the stud 80, the slide 40 and the form carried thereby may be brought into the proper vertical adjustment for the thickness of the insoles which are to be operated upon.

The mechanism for depressing the outer form against the feather at the toe of the insole comprises a vertically movable cylindrical slide 90 upon which the form is mounted and which is operatively connected with the lever 58 by means of which the inner form is depressed. As shown, the outer form is removably secured to the slide 90 by means of a headed bolt 92, which extends through a horizontal slot 94 (Fig. 11) in a lug 96 rising from the form, and is threaded into the slide, the bolt binding the rear of the form against a flat face 98 formed on the front of the slide. The slot 94 is open at one end so that the form may be removed from the slide by merely loosening the bolt 92. To maintain the form with its under face parallel to the supporting table 26, a transverse rib 100, which extends across the front of the face 98 on the slide 90, is received in a groove 102 (Fig. 11) that is formed in the rear side of the lug 96. The slide 90 is freely movable vertically in a guideway 104 (see also Figs. 4 and 5) which is formed integral with the work table 26 and is slotted, as shown at 106, to permit 110

vertical reciprocation of the outer form. The slide 90 is prevented from turning in the guideway 104 by the lug 96 on the outer form which projects beyond the sides of the 5 slide and engages bearing faces 108 on the guideway at opposite sides of the slot 106. The engagement of the lug 96 with the bearing faces 108 thus determines the horizontal angular position of the outer form. The 10 slide 90 is yieldingly actuated so that the outer form will properly engage feathers of varying thicknesses without the necessity of adjustment. To this end the upper portion of the slide 90 is reduced in diameter to form 15 a post 110 which extends loosely through an opening 112 in an ear 114, the latter projecting laterally from the lever 58 on the opposite side from the ear 68. A spring 116 surrounding the post 110 engages at one end 20 a washer seated against a shoulder 118 formed at the junction of the post 110 with the main portion of the slide 90. At its opposite end the spring 116 engages a collar 120 having a convex bearing surface to en- 25 gage against a concaved wall on the under side of the ear 114. The upper end of the post 110 is screw threaded to receive a nut 122 which is also provided with a convex bearing surface for engaging a concaved 30 wall on the upper side of the ear 114 and is held in place on the post by a lock nut 124. By means of this construction of the slide 90, the form carried thereby is yieldingly de- 35 pressed by the lever 58 as the latter is actuated to depress the inner form. As soon as the outer form has been brought into press- 40 ing engagement with the feather, which occurs before the inner form has been moved into contact with the insole, the spring 116 yields while the lever 58 continues to move the inner form downwardly.

After the outer and inner forms have been depressed into engagement with the insole, the inner form is moved horizontally toward the outer form to mold the lip into the required shape. The inner form is given its horizontal or lip-engaging movement by 45 means of the slide-carrier 52, which is dovetailed to move horizontally in guideways 128 (Fig. 1) formed in the transverse portion of a substantially U-shaped bracket 130. As 50 shown in Figs. 2 and 6, the bracket 130 projects forwardly from the upward extensions of the sides 16 of the head 12 and extends 55 horizontally above the work table 26, the oppositely disposed arms of the bracket being secured, at their free ends, to said upward extensions by means of bolts 132. This construction leaves free space at both sides of 60 the forms for the manipulation of the sole. The means for actuating the slide-carrier 52 comprises a cam lever 134, the lower end of 65 which is pivotally mounted upon a fixed stud 136 projecting inwardly from one of the sides 16. At its upper end the cam lever

134 is provided with a rearwardly projecting arm 138 carrying a cam roll 140 which is received in a suitable groove in the cam disk 64. The cam lever 134 is operatively connected with the slide-carrier 52 by a horizontal rod 142, (Fig. 6) one end of which is pivotally connected with the upper end of the cam lever. The rod 142 extends forwardly through a central recess in the horizontally movable slide-carrier 52, the vertically movable slides 90 and 40 being slotted, as indicated at 144 and 146, respectively, to permit its passage therethrough and to permit vertical movement of said slides without interfering with the rod. The central recess 70 in the slide-carrier 52, through which the rod 142 extends, is counter bored, as shown at 148, to receive a coil spring 150. The spring 150 surrounds the rod 142, one end of the spring bearing against the base of the 75 counter bored recess, at the rear of the slide-carrier, and the opposite end of the spring engaging a nut 152, which is threaded onto the forward end of the rod 142, and is secured in place by means of a lock-nut 154. 80 This construction provides a yielding connection between the slide-carrier 52 and the cam-lever 134 so that after the inner form has reached the limit of its horizontal movement against the lip of the insole, further 85 actuation of the cam lever will cause compression of the spring 150 without damage to the parts. By reason of this yielding connection, no adjustment of the inner form need be made for insoles having lips of varying 90 thicknesses. By turning the nut 152 to vary the compression of the spring 150, the molding pressure exerted by the inner form 95 may be altered, a heavier or lighter pressure being produced as may be desired. In order to provide for positive movement of the inner form away from the lip of the insole, a shoulder 156, formed on the rod 142, engages the rear of the slide-carrier 52, after 100 the compression of the spring 150 has been relieved and returns the inner form to its 105 normal horizontal position.

In order to insure that the inner form will engage the channel at the base of the lip of "Economy" and like insoles, the under side of the inner form is somewhat under-cut or bevelled, as indicated at 160, in Figs. 6 to 9. By thus beveling the under side of the inner form, the marginal portion of the under side of the form is permitted 110 to seat itself in any groove or channel which may be formed in cutting an inner channel flap in the process of forming a compound lip.

After the lip has been molded into the required shape between the inner and outer forms, additional pressure is applied to the inner form, through the action of its actuating cam in the disk 64, to force the marginal portion of the bevelled lower side of the 125 130

- form firmly against the channelled portion of the insole. Inasmuch as the inner form at this time is held yieldingly against the inner side of the lip, this additional pressure upon the form causes said marginal portion thereof to apply heavy downward pressure exactly at the base of the lip. This operation assists in setting the lip so that it will retain its molded contour.
- 10 It is obvious that in cases where it is desirable to have the lip of the finished insole inclined either inwardly or outwardly from a plane normal to the insole, the lip-engaging faces of the cooperating forms may be inclined sufficiently from a vertical plane to produce the desired result. In the drawings, the inner and outer forms have been constructed, as best shown in Figs. 8 and 11, with their lip engaging faces so pitched as
- 15 to mold the lip in a somewhat inwardly inclined position. With the lip thus inwardly inclined, it is easier for the operator to last the toe and to maintain the lip in proper relation to the channel guide during
- 20 the operation of sewing the upper to the insole.

In order to return the inner and outer forms to their normal elevations above the work table to permit the removal of the insole, the bell-crank lever 60 is rocked by its cam in a direction to relieve the compression of the spring 74. When the shoulder 72 on the rod 66 engages the ear 68 on the lever 58 the latter, together with the slide 40 and

30 the inner form 32, will be positively raised. As the lever 58 moves upwardly, the compression of the spring 116 is also relieved and finally, when the ear 114 engages the nut 122 on the post 110, the slide 90 and

35 the outer form which is carried thereby, are positively raised to their normal positions.

The main shaft 22 of the machine is actuated by means of a constantly rotating driving pulley 162 which is mounted loosely on said shaft and arranged to be connected thereto by clutch mechanism which is adapted to be thrown into operation by the operator after the insole has been positioned upon the work table and to be automatically thrown

40 out of operation after the shaft has completed a single revolution. A pin-type clutch of well known construction is employed. As indicated in Figs. 1, 3 and 6, the clutch comprises a bushing 164, fast on the main shaft, the bushing projecting into a recess in the hub of the pulley, and a clutch pin 166 which is mounted for horizontal sliding movement through the bushing to bring its inner end into or out of the path of one or the other

45 of two driving lugs 168 carried by the pulley. A spring 170, seated within a recess in the bushing 164, acts upon a projection 172 on the clutch pin and tends to force the clutch pin into position to be engaged by one of

50 the driving lugs 168. To the outer end of

the clutch pin 166 is secured a head 174 which is provided with an inclined face 176, as best shown in Fig. 3. The face 176 is adapted to cooperate with a clutch controlling member in a well known manner. In

55 the construction shown, the clutch controlling member comprises an arm 178 which is movable toward and from the main shaft. To this end the arm 178 is fast upon a rock-shaft 180 that is journaled in a bearing 182

60 on the head 12. At its upper end, the clutch controlling arm 178 carries a stud 184, shown in dotted lines in Fig. 6, which normally engages the inclined face 176 on the head 174, the arm 178 being urged toward the

65 main shaft to maintain the stud 184 in engagement with the head by means of a spring 186 (Fig. 6) which acts upon an arm 188 that is fast upon the rock-shaft 180.

When the clutch controlling arm 178 is

70 in its normal position, as shown in Fig. 6, the clutch pin 176 will be held retracted so that it cannot be engaged by the driving lugs on the pulley 162. The clutch is then

75 inoperative and the pulley will rotate freely

80 while a braking device holds the main shaft stationary.

The braking device comprises a brake disk 190, which is fast on the main shaft, and a brake shoe 192, carried by the rock-shaft

85 180 and arranged to engage the periphery of the brake disk. In order that the brake shoe 192 may be actuated to disengage the

90 brake disk when the clutch controlling arm 178 is moved away from the main shaft, and to grip the brake disk when said arm is moved in the opposite direction, the brake shoe is pivotally mounted on an eccentric sleeve 194 which is secured to the rock-shaft

95 180. The eccentric sleeve 194 is provided with an extension 196 (Fig. 3) concentric with the axis of the rock-shaft 180, which extends through the bearing 182. The outer end of the concentric extension 196 is slotted as indicated at 197 and provided with

100 a clamping screw 198 by which it is clamped to the shaft. By loosening the screw 198 and shifting the eccentric sleeve radially on the shaft, the brake shoe may be adjusted

105 relatively to the brake disk to compensate

110 for wear.

When the clutch controlling arm 178 is

115 swung in a direction to withdraw the stud 184 from the inclined face on the head 174, the clutch pin will be projected into position to be engaged by one of the lugs 168 on the driving pulley, thereby connecting the pulley with the main shaft. As the

120 clutch controlling arm is thus moved, the resulting oscillation of the rock-shaft 180

125 and the eccentric 194 disengages the brake shoe 192 from the brake disk 190 to permit the rotation of the main shaft.

The clutch controlling arm 178 is actuated

130 to render the clutch operative or inoperative

by mechanism controlled by a foot treadle (not shown). This mechanism comprises an arm 200, (Fig. 6) which is formed integral with the clutch controlling arm 178 and carries a latch 202 pivotally connected, by means of a stud 204, with the bifurcated end of said arm. The latch projects between the ends of a forked arm 208 which is pivotally mounted on the fixed stud 136, and the hooked lower end of the latch is adapted to be engaged by a pin 210 carried by the arm 208. The forward end of the arm 208 is pivotally connected to the upper end of a rod 212, the lower end of which is connected with the foot treadle. The latch 202 is normally held with its hooked end in engagement with the pin 210 by means of a "grasshopper" spring 214 which is coiled about the pivot stud 204, one end of the spring bearing against a pin 216 on the arm 200 and the other end of the spring bearing against a stud 218 on the latch. When the treadle is depressed, the rock-shaft 180 and the eccentric sleeve 194 are rotated in a direction to disengage the brake shoe from the brake disk, leaving the main shaft free to rotate, and the clutch operating arm is swung outwardly through movement of the latch 202, to render the clutch operative to connect the main shaft with the driving pulley.

In order that the clutch operating mechanism may automatically return to its normal position to disconnect the clutch after a single revolution of the main shaft, irrespective of whether or not the operator releases the treadle, provision is made for disengaging the latch 202 from the pin 210 immediately after the start of a cycle of operations of the machine. This is accomplished by means of a cam lever 220 (Fig. 6) which is pivotally mounted at its lower end upon the head 12 and carries at its upper end a cam roll 222, which rides in the same cam groove in the cam disk 64 in which the cam roll 140 is received. The cam lever 220 is connected to withdraw the latch 202 from the pin 210 by means of a rod 224, one end of which is pivoted to the cam lever, while the opposite end of the rod is slotted, as indicated at 226, to receive the stud 218 on the latch. When the lever 220 has disengaged the latch from the pin 210 the spring 186, acting through the arm 188, swings the clutch operating arm inwardly until the stud 184 thereon engages the periphery of the head 174. Just before the main shaft has completed a single revolution the stud 184 is permitted to move inwardly into the path of the inclined face 176 and continued rotation of the shaft causes said face to move across the stud 184, withdrawing the clutch pin 166 from the path of the lugs 168 on the driving pulley. The rotation of the rock-shaft 180

caused by the final inward movement of the clutch operating arm causes the brake shoe 192 to grip the brake disk and arrest the rotation of the main shaft. The machine thus automatically stops after it has completed a single revolution with the forms 30, 32 and the work table 26 in the relative positions shown in Figs. 2 and 6, as above explained. When the operator releases the treadle a treadle spring (not shown) swings the arm 208 upwardly against a stop 228 on the head 12, causing the pin 210 to be again engaged by the latch 202 and thus restoring the clutch operating mechanism to normal position preparatory to initiating the next cycle of operations of the machine.

It is not deemed necessary to illustrate and describe the particular form of the cam grooves employed on the cam disk 64 as any person skilled in the art, by the exercise of ordinary mechanical skill could construct such cam grooves from the foregoing description of the construction, organization and mode of operation of the machine.

While it is preferred to employ the specific construction and arrangement of parts shown and described, it will be understood that this construction and arrangement is not essential except so far as specified in the claims and may be changed or modified without departing from the spirit and true scope of the invention.

What is claimed as new, is:—

1. A machine for operating upon lipped soles having, in combination, a support for the sole, inner and outer lip-shaping members, and means for yieldingly actuating the outer member to press the feather of the sole against the support and for thereafter relatively moving said members to shape the lip between them.

2. A machine for operating upon lipped soles, having, in combination, an unyielding support for the sole, inner and outer lip-shaping members above the support, and means for depressing the outer member yieldingly to press the feather of the sole against the support and for thereafter moving the inner member both vertically and laterally to shape the lip between said members.

3. A machine for shaping soles already provided with lips having, in combination, a support for the sole, a form for engaging the outer side of the lip and the adjacent portion of the feather of the sole, a second form for engaging the inner side of the lip, means for relatively actuating the support and the outer form in a direction perpendicular to said support to press the feather against the support and means for then relatively actuating the forms transversely of the support to shape the lip between the forms.

4. A machine for shaping soles already

provided with lips having, in combination, an unyielding support for the sole, cooperating forms at the inner and outer sides of the toe portion only of the lip for shaping the 5 lip to a predetermined contour, both of said forms being normally retracted from the support, means for moving each of said forms in a direction perpendicular to said support into contact with the sole and for thereafter relatively moving said forms laterally to shape the lip between them.

5. A machine for operating upon lipped soles having, in combination, a support for the sole, inner and outer forms for engaging 15 the lip of the sole and means for first moving the outer form in a direction perpendicular to said support to clamp the feather of the sole and for then moving the inner form toward the outer form to shape 20 the lip to a predetermined contour.

6. A machine for operating upon lipped soles having, in combination, a support for the sole, inner and outer forms for engaging the opposite sides of the lip of the sole, and 25 means for yieldingly moving the inner form toward the outer form to shape the lip to a predetermined contour.

7. A machine for operating upon lipped soles, a support for the sole, a pair of forms 30 for engaging the opposite sides of the lip and adjacent portions of the sole, means for yieldingly actuating both forms in a direction perpendicular to said support to press the sole against the support, and 35 means for relatively actuating the forms to shape the lip to a predetermined contour.

8. A machine for operating upon lipped soles having, in combination, a support for the sole, cooperating forms for engaging the 40 opposite sides of the lip of the sole and means for yieldingly actuating both forms in a direction perpendicular to said support to press the sole against the support and for thereafter actuating one form toward the 45 other to shape the lip to a predetermined contour.

9. A machine for operating upon lipped soles having, in combination, an unyielding support for the sole, a form for engaging 50 the outer side of the lip and adjacent portion of the feather at the toe of the sole, a cooperating form for engaging the inner side of the lip, means for yieldingly actuating the first form to press the feather against the support, and means for actuating the second form yieldingly toward both the support and the first form to mold the lip between the forms.

10. A machine for operating upon lipped soles having, in combination, a support for the sole, an outer form for engaging the outer side of the lip and adjacent portion of the feather at the toe of the sole and yieldingly pressing the feather against the support, an inner form for engaging the op-

posite side of the lip, and mechanism for then actuating the inner form to compress the lip against the outer form.

11. A machine for shaping soles already provided with lips having, in combination, 70 a support for the sole, a form having a shaping surface corresponding to the general contour of the lip of the sole at the toe and normally positioned to engage the lip as the sole is positioned on the support, a cooperating form for engaging the opposite side of the lip, and means for actuating the cooperating form to compress the lip against the first form.

12. A machine for shaping soles already 80 provided with lips having, in combination, a support for the sole, a form having a shaping surface corresponding to the general contour of the lip of the sole at the toe and normally positioned to engage the outside 85 of the lip as the sole is positioned on the support, a second form for engaging the inside of the lip, and means for actuating the second form laterally of said support and toward the first form to compress the 90 lip against the latter form.

13. A machine for operating upon lipped soles having, in combination, a support for the sole, a form for engaging the outside 95 of the lip and adjacent portion of the feather of the sole normally positioned to permit the insertion of the feather between the form and the support and to engage the outside of the lip when the sole is placed 100 upon the support to longitudinally position the sole for the operation to be performed thereon, means for actuating the form to press the feather against the support, a second form for cooperating with the first 105 form to mold the lip, and means for actuating the second form.

14. A machine for operating upon channeled soles having, in combination, a support for the sole, a form for engaging 110 the outer side of the channel lip at the toe of the sole, a second form having a contour to fit within the space between the converging toe portions of the lip and a sole-engaging face beveled to project into the channel, and means for actuating the second 115 form to press the sole against the support and to mold the lip between the first and second forms and thereafter to increase the pressure of the second form to facilitate the 120 setting of the lip.

15. A machine for operating upon lipped soles having, in combination, a support for the sole, an outer form for engaging the outer side of the lip and adjacent portion of the feather at the toe of the sole, mechanism for 125 first actuating said form to press the feather against the support, an inner form for engaging the opposite side of the lip, and mechanism for subsequently actuating the inner form to shape the lip between said forms and 130

thereafter to exert a heavy pressure on the sole and against the support.

16. A machine for operating upon lipped soles having, in combination, cooperating forms for engaging the opposite sides of the lip of the sole to mold the lip to a predetermined contour, and mechanism for actuating one of the forms including a slide for said form, a slide-carrier having a guide-
10 way for the slide, a fixed support having a guideway for the slide-carrier, means for actuating the slide to bring the form carried thereby into engagement with the sole, and means for yieldingly actuating the slide-carrier to bring the forms into cooperative molding relation.

17. A machine for operating upon lipped soles having, in combination, a frame, a work table carried by the frame for supporting the sole, cooperating inner and outer forms for engaging opposite sides of the lip at the toe of the sole, means for moving the inner form toward the other form to shape the lip, and a bracket secured to said frame
20 at the rear of the work table and projecting forwardly and centrally above the table for guiding said inner form during its shaping movement.

18. A machine for operating upon lipped soles having, in combination, a support for the sole, cooperating inner and outer forms movable toward and from said support and into engagement with opposite sides of the lip of the sole, power mechanism for actuating said forms, and automatic means for throwing said power mechanism out of operation and for stopping the machine with one of the forms in a position to engage the lip of the sole as the sole is moved over
30 said support.

19. A machine for operating upon lipped soles having, in combination, a horizontal support for the sole, cooperating inner and outer forms movable vertically toward and from said support and also into engagement with opposite sides of the lip of the sole, power mechanism including a one-revolution clutch for imparting said movements to the
40

forms, and automatic means for throwing said power mechanism out of operation and
50 for stopping the machine at the completion of a single cycle of operations with the inner form positioned vertically above and the outer form positioned vertically below the top of the lip of the sole so as to permit the
55 insertion of the feather of the sole between the forms and the support with the lip of the sole engaging the outer form.

20. A machine for operating upon lipped soles having, in combination, a support for the sole, cooperating forms for engaging the inner and outer sides of the lip at the toe of the sole to shape the lip to a predetermined contour, both of said forms being normally retracted from the support, a
60 single lever and connections for bringing both forms into contact with the sole, and means for operating the lever.

21. A machine for operating upon lipped soles having, in combination, a support for the sole, cooperating forms at the inner and outer sides of the toe end of the lip for shaping the lip to a predetermined contour, both of said forms being normally retracted
70 from the support and adapted to be depressed to press the sole against the support, and means constructed and arranged to depress the outer form to hold the sole and thereafter to depress the inner form.

22. A machine for operating upon lipped soles having, in combination, a support for the sole, cooperating forms at the inner and outer sides of the toe end of the lip for shaping the lip to a predetermined contour, both of said forms being normally retracted
80 from the support and adapted to be depressed to press the sole against the support, means constructed and arranged to depress said forms to hold the sole against the support and thereafter to impart additional
85 pressure to the inner form, and means for relatively actuating the forms to shape the lip before additional pressure is imparted to the inner form.

JOHN W. COSGROVE.
